UNITED STATES PATENT OFFICE.

DAVID A. EBINGER AND DAVID H. EBINGER, OF COLUMBUS, OHIO.

WATER-CLOSET STRUCTURE.

1,213,343.

Specification of Letters Patent. Patented Jan. 23, 1917.

Application filed January 10, 1914. Serial No. 811,290.

To all whom it may concern:

Be it known that we, DAVID A. EBINGER and DAVID H. EBINGER, citizens of the United States, residing at Columbus, in the 5 county of Franklin and State of Ohio, have invented certain new and useful Improvements in Water-Closet Structures, of which the following is a specification.

Our invention pertains to water closet 10 structures and aims particularly to provide a type of structure and arrangement to comply with all sanitary requirements and also a structure that may be readily manufactured and easily set in position.

15 Our invention especially aims to provide a novel type of mounting for the bowl structure. In practically all cases where the floor and side wall join, the angle of meeting is not of a true 90 degrees, or either one or both may be slightly warped or otherwise 20 distended and it is necessarily a somewhat difficult task to properly place a bowl if such bowl is adapted to rest on the floor and also abut the wall. Further, this type of 25 mounting always produces a filth about the floor and presents lines of connections which are not readily cleaned. We, therefore, provide a structure for directly mounting the bowl from the side wall and somewhat 30 spaced from the floor level. We are aware that this idea is not broadly new, as structures have been provided heretofore which rely essentially upon a small portion of the porcelain ware to sustain the entire load.

35 However, this method of mounting frequently causes a breaking away of the porcelain and we have, therefore, provided a bracket entirely independent of the bowl structure and adapted to be securely fastened 40 to the side wall, this bracket carrying outwardly projecting formations to engage the outer periphery of the bowl to effect a support. In its preferred form, these outwardly extending projections are all formed 45 in one to practically envelop the entire lower portion of the bowl following its contour as much as is desired, and engaging the flush rim to form the supporting surface.

In the use of a structure such as this, we 50 may provide a separate partition member somewhat spaced from the wall and to this partition member we directly attach my supporting bracket. The bowl itself is provided with water inlet and outlet openings 55 and also a vent opening, preferably beneath the water inlet opening, the various vent

and water pipe connections being placed between the rear wall and the partition. Also, by mounting the bowl in somewhat spaced relation with the floor, the soil pipe may be 60 mounted directly upon the floor and thus avoid tearing up of the floor or the carrying of the pipe upon the ceiling of the floor below.

Other objects of our invention become 65 more apparent after a further detailed description of the accompanying drawings, in which similar characters of reference designate corresponding parts, and in which:

Figure 1 is a longitudinal vertical section 70 through a bowl showing our improved bracket carried by some type of supporting wall, Fig. 2 is a transverse section of the structure shown in Fig. 1, and, Fig. 3 is a vertical section through one of the stalls to 75 which our invention is applicable.

In the drawings, we have shown a porcelain bowl structure at 1, this bowl being provided with a water outlet 2 and being formed adjacent its upper edge as at 3 with 80 a horn accommodating a water inlet opening 4 which is in communication with the flush rim 5 and also a vent opening shown at 6, which vent opening is in communication with the interior of the bowl. Attention is 85 directed to the fact that the water inlet opening is slightly above the vent opening, this arrangement being exactly the inverse of the construction now in use. Reference particularly to Figs. 1 and 2 will show that 90 the flush rim 5 is provided with an external overhanging lip 7 which projects downwardly a slight distance to form a groove 8. This groove and lip structure preferably continues about the bowl structure and is 95 adapted to form a seat for the outwardly projecting portion 9 of the supporting bracket 10. It will be noted that the outwardly projecting portion is of pocket form to entirely envelop the lower portion of the 100 bowl and also that it is slightly curved to get a pleasing effect and to follow the contour of the bowl as much as is desired. It is not essential that this outwardly projecting portion be of a nature to form an envelope, but it is desirable in as much as the 105 peculiarly formed exterior of the porcelain bowl itself is somewhat hard to keep clean. It will be noted that the bracket itself is attached to either the side wall or a partition directly by means of the bolts 11 and in this manner the entire weight is sustained 110

by the bracket. In the drawings, we have shown a partition member, this partition member being designated by the numeral 12 and being provided with an aperture 13 to receive the inwardly projecting portions of the porcelain bowl, the upper edge of the horn 3 being provided with a flange 14 which may be used in the well known manner to form a close joint. To further insure against the accidental or malicious removal of the bowl from its applied position, we have provided the bolts 15 which are securely fastened to the porcelain member and also to the supporting bracket as is shown at 16. We preferably continue the seat supporting posts through the porcelain member and into the bracket as is shown, but this latter construction is not absolutely necessary.

20 By the use of the partition member 12, a supplemental room is formed between such partition and the side wall of the room or, where two batteries are used back to back, between the two partitions 12. This room is used to advantage in a number of ways and essentially provides a space for mounting the flush tank 17 and the vent fitting 18. It will be noted that the flush tank is connected to the bowl structure through the pipe 19 and the vent fitting by means of a pipe 20, these pipes not interfering with each other in any way. It is an advantage to form the bowl with the water opening above the vent opening, for the reason that specially constructed fittings need not be provided to prevent the interfering of the two pipe connections as is shown clearly in the drawings, where it must be apparent that were the water opening below the vent opening, the water pipe would have to be so formed as to fit the

vent pipe in its upward passage. Fig. 3 also shows that the soil pipe 21 may be mounted directly upon the floor for the reason that the water outlet 2 is at some elevation.

Where structures of this type are used in public buildings, and school houses, there are frequently times when they are not in use for some considerable length of time and are apt to freeze during the winter season. Therefore, the provision of the partition 12 provides an additional room and this room may be kept heated in any desirable manner to avoid freezing, such as a gas jet shown at 22.

From the above description, it must be apparent that we have provided an improved type of structure and further that the manner in which the bracket is mounted and used, avoids breaking of the porcelain bowl and permits its support in spaced relation with the floor.

What we claim is:

A water closet structure comprising a bowl formed with a peripheral flush rim, a bracket formed independently of said bowl and arranged to be directly attached to the room wall above the floor level, said bracket being formed with a forwardly extending portion upon which the flush rim of said bowl is arranged to rest, and seat post bolts extending vertically through said bowl and rigidly engaging said bracket to securely hold said bowl in position.

In testimony whereof we affix our signatures in presence of two witnesses.
